TRACK RAIL JOINT

Edmund M. Livingston, Edgewood, Pa.

Application June 18, 1936, Serial No. 85,829

8 Claims. (Cl. 238—244)

This invention relates to track rail joints, that is to say, to means for securing together the contiguous ends of aligned sections of railroad track rails.

In the main, my invention is directed toward the provision of a rail joint structure wherein the parts are so organized as to not only reinforce the rails against lateral flexure along the length of the joint, but which will, as well, effectively brace the center webs of the adjoining rail sections, and at the same time vertically stiffen said rail sections against vertical flexure under load,—all to the end of rendering the joint substantially rigid and minimizing wear of its component parts.

In connection with a rail joint structure having the above attributes, it is a further aim of my invention to make possible, through wedge action between the component parts, the taking up of wear as it occurs in the joint after extensive periods of service.

Another object of my invention is to provide rail connecting means wherein the parts are adaptable to the formation of effective joints in instances where the heads of old rails are worn adjacent the ends of adjoining sections or where the rail base flanges are worn at the end regions of the joints.

Still other objects and attendant advantages of this invention will be manifest from the detailed description following in connection with the attached drawings, wherein Fig. I is a fragmentary view in side elevation showing a four bolt track rail joint embodying my invention.

Fig. II is a cross sectional view of the joint, taken as indicated by the arrows II—II in Fig. I, and drawn to a larger scale.

Figs. III and IV are perspective views respectively of one of the splice bars and one of the wedge bars comprised in my improved joint.

Fig. V is a side view of the wedge bar shown in Fig. IV.

Figs. VI and VII are views corresponding to Fig. V showing slightly modified forms of wedge bars adapted to be used at worn joints; and,

Fig. VIII is a side view of a six hole splice bar constructed in accordance with my invention.

With detailed reference first more particularly to Figs. I and II of these illustrations, the numeral 10 indicates the contiguous ends of two rail sections which meet at the joint, the split of the joint being indicated at 11. The joint organization of my invention, it will be observed, comprises a pair of splice bars 12, 12, which are exact duplicates of each other. As shown in

Fig. II, these splice bars are of substantially channel cross sectional configuration and characterized by outwardly-bowed flexible vertical webs 13 that connect top and bottom flanges 14, 15. At their bottoms, the splice bars 12 are reinforced by outward continuations 15a of the flanges 15; and it will be noted that said bars are so proportioned as to fit, flanges first, into the side hollows of the aligned rail sections 10 at opposite sides of the vertical center webs 16. The top faces of the flanges 14, it will be further observed from Fig. II, are sloped as at 17 to correspond with the slopes 18 of the bottom faces of the rail head 19. Similarly, the bottom faces of the lower flanges 15 of the splice bars 13 are sloped as at 19 to correspond with the declination 21 of the base flanges 22 of the rails 10.

My improved joint further comprises wedge bars 23 which correspond in length to the splice bars 12 and which in turn fit the hollows of said splice bars. The upper and lower edges of the wedge bars 23 are sloped outwardly contrariwise at an acute angle as at 24, 25 to correspond with and engage complementary slopes 26, 27 respectively at the bottoms of the top flanges 14 of the splice bars and the tops of the lower flanges 15 of said splice bars. The backs of the wedge bars are curved as at 28 and adapted to abut the center web 16 of the rail at opposite sides, the curvature of the wedge bars being somewhat less than that of the rail sides so as to permit rocking and positional-self adjustment of said wedge bars in respect to the splice bars. As shown in Figs. I and III, the splice bars 12 are in this instance provided with four holes 29 through their bowed webs 13 substantially midway of the height of the latter, while the wedge bars 23 are similarly provided with holes 30 at corresponding intervals as shown in Fig. IV for passage of draw bolts such as indicated at 31 in Figs. I and II. As shown in Fig. III, the holes 29 in the splice bars 12 are made elliptic to receive the correspondingly shaped portions 31a of the bolts 31. The holes 30 in the wedge bars 23, on the other hand, are made circular to conform with the cross section 45 of the shanks of the bolts 31. For a purpose hereinafter explained, the splice bars 12 are longitudinally slit as at 32 between the inner two of the bolt holes 29.

In making up the joint, the splice bars 12 and the wedge bars 23 are assembled at opposite sides of the joint as shown in Fig. II, and the bolts 31 passed through the apertures 29, 30 in the parts 12 and 23, and also through pre-allocated registering apertures 33 in the vertical 55

center webs 16 of the rail ends 10. As the nuts 34 associated with the bolts 31 are tightened, it will be evident from Fig. II that, by the action of the wedge bars 23, and pull of the bolts, the splice bars 12 will be drawn inward and their curved webs 13 flattened. This action is attended by vertical expansion of the splice bars 12 whereby the sloping surfaces at 17 and 20 are brought into firm contact with the contiguous sloping surfaces 18, 21 of the rail heads and base flanges, and the surfaces 26, 27 similarly brought into firm contact with the contiguous surfaces 24, 25 of the wedge bars 23, the latter being free to rock on the curved sides of the web 16 of the rail to accommodate the action. With the parts assembled and secured as illustrated in Fig. II, the contiguous ends of the rail sections 10 are effectively braced both against up and down and lateral flexure, the overhangs of the rail heads 19 being supported along the dotted lines x-x in Fig. II through interposition between said head and the rail base flanges 22, of the flanges 14, 15 of the splice bars 12 and the wedge bars 23. In other words, the arrangement in effect provides between the heads 19 of the rail sections 10 and the rail base flanges substantially solid columns of metal which greatly add to the rigidity of the joint as a whole and strengthen it to better withstand the loads of passing trains. At the same time, the wedge bars 23, by abutting the center webs of the rails 10 brace the latter throughout their height and thus stiffen the joint against lateral flexure.

As a consequence of being slotted at 32, the splice bars 12 have the capacity to yield more readily to being vertically expanded by the wedge bars 23 incident to drawing up of the bolts 31 as above explained. The slits 32 may however be omitted if desired without impairing the action of the splice bars. In the latter case, however, greater effort will have to be expended in drawing up on the bolts 31.

As wear occurs in the joint, it may be taken up from time to time simply by drawing up tighter on the bolts 31 to bring the wedge surfaces of the several parts into closer contact as required. In order to prevent the formation along the wedge surfaces of the parts of shoulders such as would be likely to interfere with the efficiency of the joint, I preferably round the upper and lower flanges 14, 15 of the splice bars 12 as at 35, 36 and cut back the slopes 27 of the flanges 15 adjacent the webs 13 as at 37, 38.

For new rails, I employ in conjunction with the splice bars 12, wedge bars 23 having absolutely straight and parallel top and bottom edges as shown in Figs. I, IV and V.

In the modified wedge bar 23b delineated in Fig. VI, the upper edge slopes downward from the center 39 at a slight angle indicated in each instance at 40 toward the opposite ends 41 of the bar. This modified bar 23b is designed for use with rail sections wherein the bottom faces of the heads have been worn adjacent the split of the juncture. The effect of the bars 23b in an assembled joint will, under the drawing action of the bolts 31, be to raise the center portions of the top flanges 14 of the splice bars 12 into contact with the worn areas above referred to of the rail heads, so as to effectively brace the rail at such worn regions.

The modified form of wedge bar 23c illustrated in Fig. VII is somewhat arched, that is to say, both its top and bottom edges decline at a slight angle outward from the center 39c toward the

ends 41c as will be seen by comparison with the dot-and-dash horizontal lines shown at 42, 43. Bars of the type 23c are thus useful in instances where the base flanges of the rail or the splice bars 12 have been worn at the end regions of the joint. When incorporated in the joint, the wedge bars 23c will warp, i. e., adapt the splice bars 12 to the channel configuration of the rail sections at the worn regions aforesaid.

Fig. VIII shows a six hole splice bar 12d, which, except for having two additional bolt holes and being longer than the splice bar of Fig. III, is identical with the latter, its slit 32d being continuous through the four bolt holes 29d at the center of the bar. Obviously, the wedge bars to be used in association with the splice bar 12d of Fig. VIII are made to a corresponding length and similarly provided with six bolt holes.

To those skilled in the art, it will be apparent from the foregoing that I have provided a novel joint organization whereby the ends of the contiguous rail sections are connected more rigidly and solidly than is possible with joints of ordinary construction. Accordingly through my invention, the rails are more effectively strengthened and brace both against vertical and lateral flexure with attendant minimization of wear of the parts and assurance of correspondingly greater longevity of the joint.

Having thus described my invention, I claim: 30

1. A track rail joint comprising a pair of vertically-expansible channel section splice bars adapted to engage, flanges first, into the hollows of the aligned rail sections, the top and bottom flanges of said bars being tapered for wedging 35 action respectively with the rail heads and base flanges of said sections and connected by outwardly-bowed flexible webs; wedge bars with convexed backs abutting opposite sides of the vertical webs of the rail ends and in turn adapted to engage the hollows of the splice bars, said wedge bars having their top and bottom longitudinal surfaces counter-sloped outwardly for wedging action with the in-sides of the splice bar flanges; and transverse bolts operative to draw inward 40 upon the bowed webs of the splice bars.

2. A track rail joint comprising a pair of outwardly-bowed vertically-expansible channel section splice bars adapted to engage, flanges first, into the hollows of the aligned rail sections at 50 opposite sides of the joint; wedge bars with convexed backs abutting opposite sides of the convexed vertical webs of the rail sections and adapted in turn to wedgingly fit the hollows of the splice bars, the backs of said wedge bars having a curvature of a radius less than that of the rail web sides; and transverse bolts operative to draw the splice bars inward to coact with the wedge bars, said wedging fit normally opposing inward movement of the splice bars. 60

3. A track rail joint comprising a pair of channel section vertically-expansible splice bars to fit, flanges first, into the side hollows of the aligned rail sections, said bars having outwardly bowed flexible webs, the tops of the upper flanges being 65 sloped to correspond with and to engage the under faces of the rail heads, and the bottoms of the lower flanges being sloped to correspond with and engage the top faces of the rail base flanges; wedge bars in turn fitting the hollows of the 70 splice bars and having convexed backs abutting opposite sides of the vertical webs of the rail sections, the top and bottom surfaces of said wedge bars being counter-sloped outwardly to engage complementary slopes respectively on the bottom 75

faces of the upper flanges of the splice bars, and the top faces of the lower flanges of said splice bars; and transverse bolts operative to draw inward upon the bowed webs of the splice bars with attendant vertical expansion of the latter by the wedge bars and determination of firm wedge contact between the several opposed sloping surfaces aforesaid, whereby the rail ends are rigidly braced both against vertical and lateral flexure.

4. In a joint for aligned rail sections wherein the under sides of the rail heads are worn adjacent the split, a pair of vertically-expansible channel section splice bars adapted to engage, flanges first, within the side hollows of the aligned rail sections, the flanges of said splice bars being tapered and connected by outwardly-bowed flexible webs; wedge bars with their backs abutting opposite sides of the vertical webs of the aligned track sections and in turn wedgingly fitting the hollows of the splice bars, said wedge bars having their upper and lower surfaces sloped outward contrariwise and their upper edges additionally sloped from the center toward opposite ends of said bars; and transverse bolts operative to draw inward upon the bowed webs of the splice bars with attendant warping of the latter by the wedge bars so that their upper flanges are brought into firm contact with the undersides of the rail heads, and their bottom flanges into firm contact with the rail base flanges along the length of the joint.

5. In a railroad track joint wherein the top faces of the base flanges of the aligned rail sections are worn at the end regions of the joint, a pair of vertically-expansible channel section splice bars adapted to engage, flanges first, into the hollows of the rail sections at opposite sides of the joint, the flanges of said bars being ta-

pered and connected by outwardly-bowed flexible webs; wedge bars with their backs abutting opposite sides of the vertical webs of the contiguous rail sections and in turn adapted to wedgingly fit within the hollows of the splice bars, said wedge bars being arched lengthwise and having their upper and lower longitudinal surfaces sloped outward contrariwise; and transverse bolts operative to draw inward upon the bowed webs of the splice bars with attendant warping of the latter by the wedge bars so that the upper flanges of said splice bars are brought into firm contact with the undersides of the rail heads and their bottom flanges into firm contact with the rail base flanges along the length of the joint.

6. A track rail joint comprising a pair of outwardly-bowed vertically-expansible channel section splice bars adapted to engage, flanges first, into the side hollows of the aligned rail sections, said bars having their top and bottom flanges sloped exteriorly for wedging action respectively with the heads and the base flanges of the rail sections; wedge bars with convexed backs abutting opposite sides of the vertical webs of the rail sections and having their top and bottom surfaces oppositely sloped for wedging action with the corresponding inner surfaces of the top and bottom flanges of the splice bars; and means operative to urge the splice bars inward for coaction with the wedge bars and the rail sections.

7. A track rail joint according to claim 1, wherein the webs of the splice bars are longitudinally slotted part way of their lengths between bolts.

8. A track rail joint according to claim 3, wherein the webs of the splice bars are longitudinally slotted part way of their lengths between bolts.

EDMUND M. LIVINGSTON.
